UNITED STATES PATENT OFFICE.

HUGH McCABE, OF LAWRENCE, MASSACHUSETTS.

FEED-WATER REGULATOR.

1,148,109.

Specification of Letters Patent. Patented July 27, 1915.

Application filed October 12, 1908. Serial No. 457,225.

To all whom it may concern:

Be it known that I, HUGH McCABE, citizen of the United States, residing at Lawrence, in the county of Essex and State of Massachusetts, have invented certain new and useful Improvements in Feed-Water Regulators; and I do hereby declare the following to be a full, clear, and exact description of the invention, such as will enable others skilled in the art to which it appertains to make and use the same.

The present invention relates to an improvement in feed water regulators for boilers.

15 The object of the present invention is to produce a feed water regulator which is particularly adapted to regulate the supply of water to boilers in which the water level fluctuates comparatively rapidly.

20 The present invention is a reorganization and an improvement on the construction illustrated in the applications filed by the undersigned May 11, 1908, Serial No. 432,298, and April 16, 1908, Serial No. 427,339.

25 The invention consists in the improvement hereinafter described and particularly defined in the claims.

In the accompanying drawings illustrating the preferred form of the invention, 30 Figure 1 is a front elevation of the apparatus; Fig. 2 is a side elevation showing the balanced lever cut through two of its pipes; Fig. 3 is a vertical sectional view of the supply valve; Fig. 4 is a sectional elevation 35 of the controlling valve and part of the ball lever; Fig. 5 is an elevation of the ball lever casting; and Fig. 6 is a sectional view through the controlling valve and the lever supporting trunnions.

40 The general operation of the invention is as follows:—When the water in the boiler falls below a certain level, it permits the steam to flow through a pipe which is opened by the drop of the water in the 45 water column below the end of the pipe, and the steam flows through a trunnion into a balanced lever having at one end a weight and at the other end a large hollow ball. Normally, the ball is filled with water which 50 overbalances the weight upon the other end of the lever. When the steam flows into the ball and displaces the water therein, the weight on the other end of the balanced lever overbalances the ball and the weight drops and thereupon opens a controlling 55 valve and allows steam to flow through to a

supply valve of a water-supplying means for supplying water to the boiler. The opening of the supply valve permits steam from the boiler to flow through to a steam 60 pump which pumps the water into the boiler, or permits water to flow from a hydrostatic pressure reservoir to the boiler. When the level of the water in the boiler has been raised above the end of this pipe, 65 thereby preventing access of steam to the ball, the water flows into the ball thereby causing it to overbalance the weight and to drop. This closes the controlling valve, shutting off the supply of steam to the supply 70 valve and at the same time opens an exhaust valve allowing the pressure on the supply valve to be reduced, and the supply valve thereupon automatically closes, shutting off the supply of steam or water. 75

In the illustrated embodiment of the invention, a water column 1 is connected to the boiler by a pipe 2 extending from the top of the water column to the steam space in the boiler, and by a pipe 3 from the lower end of the water column to the boiler below the water level. The lower end of the water column normally extends below the lowest level of the water in the boiler. 80

A controlling valve is connected to the upper or steam portion of the water column by a pipe 4 extending upwardly to a valve casing 5, which is laterally supported by a brace 6 secured to the pipe 2. Within the casing 5 is a valve chamber 7 having an outlet 8 connected to a supply valve, and the supply of steam from the pipe 4 to the supply valve is controlled by a controlling valve 9 mounted on the lower end of a stem 10 which passes through an exhaust chamber 11 having an outlet or exhaust 12. This stem 10 is slotted just above the controlling valve to permit the steam to escape from the valve chamber into the exhaust chamber when the controlling valve 9 is closed. Upon the upper end of the stem 10 is mounted a fork 13 pinned by a pin 14 to the projection 15 from the ball lever casting 29, hereinafter referred to. The hole in the projection 15 is elongated, as shown, to prevent cramping of the stem with oscillations of the ball lever. When the stem is pressed downwardly, the controlling valve 9 is thereby closed and when the stem is pulled up the controlling valve 9 is opened. 100

The operation of the controlling valve is regulated by a balanced lever. From the

valve casing 5 extends upwardly a yoke 16, the ends 17 and 18 of which are hollow and form bearings for two hollow trunnions 19 and 20 respectively. A pipe 21 extends from 5 the water column at the critical line to the hollow end 17 of the yoke. This pipe 21 is of restricted cross-sectional area, the purpose of which will hereinafter be explained. Connection is had between the lower portion 10 of the water column and the other end 18 of the yoke through a pipe 22 which extends from the lower end of the water column through the top of a closed well or cooling vessel 50 and through a pipe 51 which ex- 15 tends from the end 18 of the yoke to the bottom of said well. The purpose of placing the well or cooling vessel 50 in the water-conducting connection between the lower portion of the water column and the end 18 20 of the yoke will be hereinafter explained. The pipes 4, 21, 22 and 51 are all controlled by ordinary valves 23 which are normally open and should never be closed except when it may be necessary to make repairs. The 25 ends of the trunnions lying within the hollow ends of the yoke are held steam-tight by means of packing 24 compressed by ported glands 25 operated by hand-wheels 26 on stems 27 which screw into the ends 30 of the yoke ends 17 and 18 and are held by check nuts 28. The other ends of the trunnions extend toward the center of the yoke and are threaded in order to engage threaded bores and thereby pivotally support be- 35 tween them a lever casting 29 having chambers 30 and 31 which are continuations respectively of the hollow trunnions 19 and 20. These chambers 30 and 31 open respectively into two pipes 32 and 33 which extend 40 horizontally from the casting 29 and enter a ball 34 supported by them, the pipe 32 extending within the ball nearly to the top. On the opposite side of the casting 29 is a horizontally extending rod 35 carrying a 45 weight 36. The casting 29 with the rod and weight on one side and the pipes and ball on the other side, form a balanced lever pivotally mounted on the trunnions. When the ball is full of water, it overbalances the 50 weight and retains the lever in a horizontal position, and in that position the controlling valve 9 is pressed down and held closed, but when the ball is empty, the weight overbalances the lever and it is thereby caused to 55 tip up, thereby pulling the controlling valve open.

From the inlet 8 in the valve chamber 7 a pipe 38 extends to a chamber 39 in a casting 40 for the purpose of carrying steam to 60 open a supply valve. Within the chamber 39 is a piston 41 mounted on a stem 42, the lower end of which carries a supply valve 43 for opening and closing the opening between an inlet chamber 44 and an outlet chamber 65 45 connected to a steam pump. The stem 42

is held tight by packing 46 compressed by a gland 47. Underneath the piston is a helical spring 48, the lower end resting in a spring socket and the upper end engaging the under side of the piston 41 which exerts 70 pressure upon the piston and tends to keep the supply valve 43 closed at all times.

The above-described piston and means co-operating therewith to move the valve may be spoken of broadly as the supply valve actuator. A bolt 49 affords means for opening and holding open the supply valve for filling the boilers. The water column 1, the feed water or water supply valve 43, its actuating piston 41, the balanced lever, the controlling valve, and the connections between the several parts and the boiler, as described above, are constructed and arranged the same as shown and described in my application Serial No. 432,298 except 85 that the pipe 21, leading from the normal or critical level of the water in the boiler to the balanced lever, is made of restricted cross-sectional area, and the pipe connection 22 and 51, leading from the balanced lever to a point in the boiler below the normal level of the water in the boiler, is provided with a well 50. In the operation of the apparatus of said application Serial No. 432,298, it was found that sometimes, and more especially in fast steaming boilers, the fluctuations in the water level in the boiler were so rapid and the temperature of the water supplied to the balanced lever so high, that the latter did not respond with sufficient alacrity to the fluctuations in the boiler in order to maintain as uniform a level as was desired. To increase the alacrity of operation of the apparatus, the pipe connection 22 and 51 connecting with the water 95 in the boiler below the normal level thereof, is provided with a well 50, which affords a reservoir for water considerably cooler than that in the boiler, which can flow into the balanced lever when the supply of steam thereto is cut off by the rising of the water in the boiler above the critical level. In order to accentuate the increased sensitivity of the apparatus, the connection between the boiler at the critical level and the balanced lever is reduced in cross-sectional area so that the flow of water into the balanced lever, by means of this restriction, is caused to be principally drawn from the reservoir 50, and not directly from the water 100 in the boiler at the critical level, which is the place in the boiler where the water is at its highest temperature. Each of these modifications contributes to increase the sensitivity and rapidity of operation of the apparatus, the reservoir in the pipe connected with the boiler below the water level thereof by supplying cold water to the balanced lever, and the restriction of the cross-sectional area of the pipe 21 by compelling the 105 110 115 120 125 130

water to flow from the reservoir into the balanced lever.

The form of the reservoir or well is immaterial, so long as it affords an amount of 5 cooler water which will act quickly to condense the steam in the balanced lever. In the illustrated embodiment of the present invention the reservoir or well 50 is separated from and situated below the water 10 column 1. The heat is dissipated by the well to the surrounding air. Since the well is connected to the column 1 below the water level, no steam can enter the well to supply the heat dissipated therefrom to the air. It 15 is to be noted that the pipe 51 which leads the water from the cooling well 50 to the balanced lever, draws the water from the bottom or coolest part of the well. The restriction of the area of the pipe connected 20 with the boiler at the critical level may be secured either by reducing the size of the pipe or by partially closing a valve therein, or by restricting any portion of the passage-way through the lever to the ball. Of 25 course, any equivalent of this would be within the purview of the invention, as, for example, any restriction of the effective cross-sectional area as by the interposition of barriers or the increasing of the fluctural 30 resistance.

This device operates in detail as follows:— When the water in the boiler falls below the critical line it opens the end of the pipe 21 in the water column and permits steam to 35 flow up through the pipe 21, through the hollow end 17 of the yoke 16, the trunnion 19, the chamber 30 of the lever casting 29, and the pipe 32 into the ball 34, thereby displacing the water which flows out of the 40 ball through the pipe 33, through the chamber 31 in the balanced casting 29, through the trunnion 20, through the end 18 of the yoke 16, through the pipe 51 into the well 50 and back into the water column through 45 the pipe 22. With this displacement of the water in the ball by steam, the weight 36 overbalances the ball and causes the balanced lever to tip and the casting 29 moves upwardly and opens the controlling valve 50 9 and admits steam from the upper portion of the water column through the pipe 4, the valve chamber 7 and the pipe 38 to the chamber 39 where the steam pressure moves the piston 41 downwardly and opens the 55 supply valve 43. This allows steam to flow to the steam pump, by which the boiler is fed. When the water in the boiler rises above the mouth of the pipe 21, the supply 60 of steam through that pipe to the balanced lever and ball is shut off and the condensation of steam in these portions causes the water to flow up through the pipes 21 and 22, the trunnions 19 and 20, chambers 30 and 31, and pipes 32 and 33 into the ball 34. 65 Since the pipe 21 is of restricted cross-sec-

tional area, the water which flows into the ball to replace the condensed steam comes principally through the pipe 51. This water is drawn from the bottom of the cooling well 50 and is considerably cooler than the 70 water in the boiler or the water column 1. When this cooler water enters the balanced lever and ball 34, it accelerates the condensation of the steam therein, so that the ball 34 is filled comparatively rapidly with water. 75 In this state, it overbalances the weight 36 and causes the balanced lever to swing again to a horizontal position thereby closing the controlling valve 9, and shutting off the supply of steam from the pipe 4 to the supply valve. At the same time, the steam in the chamber 39 and pipe 38 exhausts through the slots in the stem 10 to the exhaust chamber 11. This reduces the pressure in the chamber 39 and the spring 48 80 lifts the piston 41 and thereby shuts off the supply of steam to the steam pump or the supply of water from the hydrostatic pressure reservoir to the boiler, as the case may be. 85

In the illustrated embodiment of the present invention, the pipe connection 21 to the balanced lever opens into the water column 1 at the normal level of the water therein, and the pipe connection 22 to the cooling 90 well 50 opens into the water column 1 below the normal level of the water therein. It is evident, however, that the pipe connections to the balanced lever and to the cooling well might open directly into the 95 boiler at the normal level of the water therein and below the normal level of the water therein respectively, and the apparatus would operate in substantially the same manner as the apparatus of the illustrated 100 embodiment. It is, therefore, within the purview of the present invention to omit the water column shown in the illustrated embodiment and to make the pipe connections directly to the boiler. 105

The expression "a steam and water space which is under boiler pressure" as used in the claims is intended to define the space at the normal water level which is alternately occupied by steam and water as the 115 water line fluctuates, whether this space is in a water column as illustrated in the preferred embodiment of the present invention, or in the boiler itself, or in any closed vessel connected with the boiler which is under 120 boiler pressure and in which the water line fluctuates with the water line of the boiler. The expression "water space which is under boiler pressure" is intended to define a space which is below the water line of the 125 boiler so as to be always occupied by water, whether this space is in the lower part of a water column below the water line therein as in the illustrated embodiment of the invention, or is in the boiler itself, or is in any 130

reservoir connected with the boiler in which the water is under boiler pressure.

Having thus described the invention, what is claimed is:—

- 5 1. A feed water regulator for boilers having, in combination, a water supply valve, an actuator therefor, a balanced hollow lever, connections between the lever and the actuator operating to open and close the supply valve with movements of the balanced lever, a closed cooling reservoir or well so situated that steam cannot enter the well from the boiler, a pipe connection to the balanced lever opening at the normal level of the water in the boiler to a steam and water space which is under boiler pressure, a pipe connection to the well opening at a point below the normal level of the water in the boiler to a water space which is under boiler pressure, and a pipe connection between the balanced lever and the bottom of the well, substantially as described. 70
- 10 15 20 25 30 35 40 45 50 55 60 65 70 75 80 85 90 95 100 105 110 115 120 125
2. A water feed regulator for boilers having, in combination, a water supplying means, and means for controlling said water supplying means, including a chamber normally filled with water, a pipe connection to the chamber opening at the normal level of the water in the boiler to a steam and water space which is under boiler pressure, and a second pipe connection to the chamber opening below the normal level of the water in the boiler space which is under boiler pressure, said connections permitting steam to flow into the chamber through the first pipe connection and displace the water therein when the water in the boiler drops below its normal level, said second pipe connection having provision for reducing the temperature of the water flowing through it to the chamber so as to cause a rapid condensation of the steam in the chamber when the water level in the boiler rises to cut off the steam from the first connection, substantially as described. 90
3. A feed water regulator for boilers, having, in combination, a water supply valve, an actuator therefor, a balanced hollow lever, and two connections to the balanced lever, one opening at the normal level of the water in the boiler to a steam and water space which is under boiler pressure, and the other opening below the normal level of the water in the boiler to a water space which is under boiler pressure, the first connection being of a restricted cross sectional area and the second connection having a cooling reservoir or well therein, substantially as described. 100
4. A feed water regulator for boilers having, in combination, a water supply valve, an actuator therefor, a balanced hollow lever, connections between the lever and the actuator operating to open and close the supply valve with movements of the balanced lever, a closed cooling reservoir or well situated below the normal level of the water in the boiler, a pipe connection to the balanced lever opening at the normal level of the water in the boiler to a steam and water space which is under boiler pressure, a pipe connection to the well opening at a point below the normal level of the water in the boiler to a water space which is under boiler pressure, and a pipe connection between the balanced lever and the bottom of the well, substantially as described. 110
5. A feed water regulator for boilers having, in combination, a water supply valve, an actuator therefor, a balanced hollow lever, a water column, pipe connections between the water column and boiler above and below the normal level of the water in the boiler, a cooling reservoir or well, a pipe connection between the balanced lever and the water column at the normal level of the water in the column, a pipe connection between the well and the water column at a point below the normal level of the water in the water column, and a pipe connection between the balanced lever and the well, substantially as described. 115
6. A feed water regulator for boilers having, in combination, a water supply valve, an actuator therefor, a balanced hollow lever, connections between the lever and the actuator operating to open and close the supply valve with the movements of the balanced lever, a water column, pipe connections between the water column and the boiler above and below the normal level of the water in the boiler whereby the column is filled partly with water and partly with steam, a cooling reservoir or well situated below the water column, a pipe connection between the balanced lever and the water column at the normal level of the water in the water column, a pipe connection between the bottom of the water column and the well, and a pipe connection between the balanced lever and the bottom of the well, substantially as described. 120
7. A water feed regulator for boilers having, in combination, a water supplying means, and means for controlling said water supplying means, including a chamber normally filled with water, a pipe connection to the chamber opening at the normal level of the water in the boiler to a steam and water space which is under boiler pressure, and a second pipe connection to the chamber opening below the normal level of the water in the boiler to a water space which is under boiler pressure, said connections permitting steam to flow into the chamber through the first pipe connection and displace the water therein when the water in the boiler drops below its normal level, said second pipe connection

nection having provision for reducing the temperature of the water flowing through the chamber so as to cause a rapid condensation of the steam in the chamber when the water level in the boiler rises to cut off the steam from the first connection, and said first pipe connection being restricted so as to cause the water to flow to said chamber principally through the second pipe con-

nection when the steam in the chamber is 10 condensed, substantially as described.

In testimony whereof I affix my signature, in presence of two witnesses.

HUGH McCABE.
